WIDE-BAND HIGH-FREQUENCY
TRANSFORMER**Donald Mackey, Haddon Heights, N. J., assignor
to Radio Corporation of America, a corporation
of Delaware**

Application June 4, 1943, Serial No. 489,663

9 Claims. (Cl. 171—777)

1

This invention relates to wide-band transformers such as may be employed in the radio frequency (R. F.) stages, or in the intermediate frequency (I. F.) amplifier stages of television or other receivers of the superheterodyne type.

It is common practice in superheterodyne receivers for reception, for example, in the broadcast band to use mutually-coupled, magnetic-core transformers as the coupling means between stages. Because of the relatively narrow band of frequencies that need be passed by such transformers they have proved quite satisfactory. However, the use of transformers of similar construction, but designed for higher frequencies such as are encountered in television and pulse reception, has been found to be unsatisfactory for the reason that only a limited range of frequencies can be transmitted thereby.

It is therefore the main object of the present invention to provide a novel core arrangement in an I. F. or R. F. transformer operating at high frequencies whereby the band-width of the transmitted frequency band is materially increased.

It is another object of the invention to secure, together with sufficient coupling, higher gain than heretofore obtained in wide-band, double-tuned I. F. or R. F. transformers as required for television and pulse reception, with a minimum of components.

Still another object of the invention is to increase the coefficient of coupling between the coils of the transformer and to maintain the coupling constant, resulting in a wider frequency band at a given frequency than heretofore obtainable through mutual magnetic coupling alone.

A further object of the invention is to obtain the required band-width by means of mutual magnetic coupling, thereby obtaining a more symmetrical response curve than that obtained by the usual methods of wide-band coupling.

Still a further object is to provide a high frequency coupling device which is constituted by a pair of inductance coils in magnetically coupled relation, a ferro-magnetic core disposed in the field of both said coils for effecting increased coupling between said coils, and a second ferro-magnetic core adjustable relatively to only one of said coils, said coils and said cores being so disposed that movement of said cores relative to their respective coils alters the effective inductance of the respective coils while maintaining the degree of coupling between them substantially constant.

The novel features characteristic of my invention are set forth with particularity in the appended claims. The invention itself, however,

2

both as to its organization and mode of operation together with further objects and advantages thereof, will best be understood by reference to the following description taken in connection with the accompanying drawing in which Fig. 1 is a view in cross-section of the coil and core arrangement utilized in conventional high frequency magnetic core transformers; Fig. 2 shows the response curve for the transformer shown in Fig. 1; Fig. 3 is a view similar to that of Fig. 1 showing the coil and core arrangement of a high frequency transformer according to the present invention; Fig. 4 shows the response curve for the transformer illustrated in Fig. 3; Fig. 5 illustrates schematically a circuit of an I. F. amplifier embodying the present invention, and Fig. 6 is a portion of the circuit of Fig. 5 illustrating schematically a modified form of transformer coupling unit in accordance with the invention.

Referring first to Fig. 1, the conventional magnetic core transformer or coupling unit is seen to comprise a primary winding 1 and a secondary winding 2 which are coaxially wound and axially spaced on a common insulating tube 3. Magnetic, powdered iron cores 4 and 5 arranged for axial movement within the tube are associated with the respective transformer windings and are adapted to adjust the inductance thereof. Adjusting screws 6 and 7 at the ends of the cores are provided for that purpose.

In the conventional transformer, the cores 4, 5 are arranged to work at opposite ends of the respective windings 1, 2 so that adjustments in core position do not affect the coupling coefficient therebetween. Thus the maximum coupling is fixed by the geometry and spacing of the two windings. An intermediate frequency transformer such as described above, but for operation in the broadcast band, is disclosed in Harvey Patent No. 2,283,924 (see Fig. 2).

In Fig. 2 of the accompanying drawing there is shown the response curve for a transformer having the construction shown in Fig. 1 (but without the coupling impedance X) and operating at 45 30 megacycles. As indicated the transformer passes the frequencies between 29 and 31 megacycles, or a band-width of 2 mc., with substantially uniform gain.

In some instances, in order to increase the coupling between the transformer windings, a coupling impedance X shown by the dotted connection between the high potential ends of the windings has been employed. The impedance may consist of a capacitance or an inductance, and while an increased band-width is obtained there-

by, losses are introduced into the circuit and the frequencies above and below the passed band are unequally attenuated resulting in an unsymmetrical response curve.

The high frequency coupling device in accordance with my invention is shown in Fig. 3 where in the primary and secondary windings 8 and 9, respectively, are placed closer together in an axial direction on the coil supporting tube 3, and the magnetic core 10, preferably the one that is associated with the secondary winding, is made somewhat longer than the space between windings and is positioned in the field of both windings. The second core 11 is associated with the primary winding 8 in the conventional manner. By virtue of this arrangement the permeability of the path from primary to secondary due to the core 10 is increased, thereby realizing an increase in coupling. Since the coupling between the coils involves solely mutual magnetic coupling, a more symmetrical response is obtained, resulting in better attenuation of signals on adjacent channels. Also, the elimination of the coupling impedance X (shown in Fig. 1), besides effecting a saving in the cost of the coupling unit, contributes to the attainment of a higher L/C ratio of the double-tuned band-pass circuits.

By making the length of the coupling core 10 shorter than the space between extreme ends of the two windings and longer than the space between adjacent ends of the two windings, the coupling core may be moved back and forth without affecting the permeability of the entire system, and hence without affecting coupling. The desired degree of coupling may be initially obtained by adjusting either the spacing between windings, or the length of the coupling core 10, or the permeability of the material used in the coupling core, or any combination of these means. Movement of the coupling core in a given direction results in an increase of inductance of one winding and a decrease in the other. Thus the secondary winding 9 may be tuned by moving the coupling core 10, and the primary winding 8 may be tuned by means of the conventionally located core 11. The latter core must provide sufficient adjustment to compensate for the adjustment position of the coupling core plus the normal variations for which adjustment of inductance is required.

While it is not generally essential that the coils differ in length, it is essential that the coil 8 be sufficiently long to accommodate the axial motion of both cores necessary to produce the required degree of adjustment, whereas the coil 9 need accommodate only the movement of the coupling core 10. It is desirable therefore, if there is to be a difference in the winding lengths, to have as the longer winding the winding that is associated with the core that serves only to adjust the inductance. In the disclosed arrangement it is the winding 8. In extreme cases, it may be necessary to deliberately make this winding longer by changing the winding pitch in order to accommodate the required adjustment.

In a practical embodiment of the coupling transformer constructed in accordance with my invention, the fiber tube 3 had an inside diameter of .253" and a length of 1 1/4"; the primary winding 8 consisted of a single layer of 22 turns of #30E wire wound to a length of 27/64"; the secondary winding 9 was axially spaced from the primary $\frac{1}{16}$ of an inch and consisted of a single layer of 15 turns of #30E wire wound to a length of 17/64"; the magnetic core 11 was .246" 75

in diameter and 1/4" long; and the magnetic core 10 was .246" in diameter and 1/2" long.

Fig. 4 shows the response curve obtained with the transformer constructed as shown in Fig. 3 and operating at the same frequency, 30 megacycles, as the transformer of Fig. 1. The frequencies that are passed with substantially uniform gain extend between approximately 27.7 and 32.2 mc., giving a band width of approximately 4.6 mc. In both cases the geometry of the windings was approximately the same so that the increased band width shown in Fig. 4 is due entirely to the core location.

In an experimental set-up a 30 mc. transformer stage, approximately 4.6 mc. wide, using the transformer of Fig. 3, showed a stage gain of 8.5. In the same set-up a capacity coupled transformer (the high potential ends of the windings connected by a coupling condenser) with the same band width showed a gain of 6.7, representing a ratio of 1.26 to 1 in favor of the transformer embodying the present invention.

Fig. 5 represents a typical I. F. amplifier circuit in which the transformer or coupling unit of Fig. 3 may be employed. The transformer primary 8 shown in this instance to extend over a greater length than the secondary is included in the plate circuit of an I. F. amplifier tube 12 and the transformer secondary 9 is connected to the signal control grid of a tube 13 which may be a second I. F. amplifier or the conventional second detector utilized in superheterodyne receivers. The magnetic cores 11 and 10 correspond to the similarly numbered cores of Fig. 3, the former serving to adjust the inductance of the primary and the latter serving to adjust the inductance of the secondary as well as to establish increased coupling between the two windings. The windings are individually adapted to be tuned by the inherent capacitance of the circuit and of the tubes to which they are coupled to form a band-pass selector for passing the intermediate frequency signals. The tuning capacitances of the windings are indicated by the dotted line condensers 14 and 15 for the reason that these capacitances may be comprised in whole or in part, preferably in whole, of the inherent capacitance of the circuit. The shunting resistance 16 across the primary is used to obtain a flat frequency response, and the resistance-capacity combination 17 connected to the cathode of each tube is the conventional self-biasing network for impressing a suitable bias on the signal control grids of said tubes.

Although I have shown and described the coupling core 10 to be the core that adjusts also the inductance of the secondary, it is to be understood that it may be chosen to adjust instead the inductance of the primary. This is shown in Fig. 6 where the iron core 10' serves to provide the increased coupling between the windings and at the same time is adapted to adjust the inductance of the primary 8', the core 11' being associated with only the secondary 9' for adjusting its inductance. In this instance the winding 9' may be of a greater length than the primary 8' as shown, since as previously mentioned it is advisable that the core which serves only to adjust the inductance be associated with the longer winding.

While I have shown and described certain preferred embodiments of my invention, it will be understood that various modifications and changes will occur to those skilled in the art without departing from the spirit and scope of this

invention. I therefore contemplate by the appended claims to cover any such modifications as fall within the true spirit and scope of my invention.

What I claim is:

1. A wide-band high-frequency transformer comprising a pair of windings which are adapted to be tuned each through a predetermined range of high frequencies, said windings being coaxially wound on a common insulating tube and so spaced as to provide a certain degree of coupling between the windings, a first axially-adjustable core of comminuted magnetic material disposed within the tube and in overlapping relation with the adjacent end portion of said windings for increasing the degree of coupling between the windings and, upon adjustment thereof, for altering the inductance of one of the windings without substantially effecting a change in the increased degree of coupling between the windings, and a second axially-adjustable core of comminuted magnetic material disposed within the tube and cooperatively related with the other winding for altering the inductance of said latter winding.

2. A wide-band high-frequency transformer comprising primary and secondary windings which are adapted to be tuned each through a predetermined range of high frequencies, said windings being coaxially wound on a common insulating tube and so spaced as to provide a certain degree of coupling between the windings, a first axially-adjustable core of comminuted magnetic material disposed within the tube and in overlapping relation with the adjacent end portions of said windings for increasing the degree of coupling between the windings and, upon adjustment thereof, for altering the inductance of the secondary without substantially effecting a change in the increased degree of coupling between the windings, and a second axially-adjustable core of comminuted magnetic material disposed within the tube and cooperatively related with the primary winding for altering the inductance of said latter winding.

3. A wide-band high-frequency transformer comprising a pair of windings which are adapted to be tuned each through a predetermined range of high frequencies, said windings being of different lengths, coaxially wound on a common insulating tube and so spaced as to provide a certain degree of coupling between the windings, a first axially-adjustable powdered-iron-core disposed within the tube in overlapping relation with the adjacent end portions of said windings for increasing the degree of coupling between the windings and, upon adjustment thereof, for altering the inductance of the shorter winding without substantially effecting a change in the increased degree of coupling between the windings, and a second axially-adjustable powdered-iron-core shorter than the first core disposed within the tube and cooperatively related with the longer winding for altering the inductance of said latter winding.

4. A wide-band high-frequency transformer comprising a pair of windings which are adapted to be tuned each through a predetermined range of high frequencies, said windings being coaxially wound on a common insulating tube and so spaced as to provide a predetermined degree of coupling between them, a pair of ferro-magnetic cores axially adjustable within said tube adapted each

upon adjustment to vary the self-inductance of one of said windings, one of said cores being disposed in the field of only one of the windings, and the other of said cores being disposed in overlapping relation with the adjacent ends of both windings so that for all adjustments the latter core is in the magnetic fields of both windings to thereby increase the coefficient of coupling between said windings to a maximum, said latter core being sufficiently longer than the spacing between the adjacent ends of the windings and sufficiently shorter than the spacing between the remote ends of the windings, that the axial movement required to produce the desired adjustment in self-inductance of the winding other than said one winding results in no appreciable change in coupling between the two windings.

5. A wide-band high frequency transformer in accordance with the invention defined in claim 4 wherein the second core which serves to increase the coupling between the windings is of a different permeability material than the first core.

6. A wide-band high-frequency transformer for a radio frequency amplifier or for an intermediate frequency amplifier of a superheterodyne receiving system, comprising primary and secondary windings coaxially wound on a common insulating tube and so spaced axially as to provide a certain degree of magnetic coupling between the windings, an adjustable ferro-magnetic core disposed within the tube and of such length that for all adjustments it overlaps the adjacent ends of said windings thereby increasing the degree of coupling therebetween, said core upon axial adjustment adapted to vary the inductance of one of the windings without affecting the degree of coupling between said windings, said core being of greater length than said one winding, and a second ferro-magnetic core movable within the other winding adapted upon adjustment thereof to vary the inductance of said latter winding, said second core being of shorter length than said other winding.

7. A wide-band high-frequency transformer in accordance with the invention defined in claim 6 wherein the second core is associated with the primary winding.

8. A wide-band high-frequency transformer in accordance with the invention defined in claim 7 wherein the second core is associated with the secondary winding.

9. A wide-band high-frequency transformer in accordance with the invention defined in claim 7 wherein the windings are of unequal axial lengths and the cores are of unequal axial lengths, the shorter core being associated with the longer winding and the longer core serving as the coupling core.
